UNITED STATES PATENT OFFICE.

CHARLES WALTER PARKS, OF POMONA, CALIFORNIA.

TRIPLEX CRANKING MECHANISM.

1,117,234.

Specification of Letters Patent. Patented Nov. 17, 1914.

Application filed July 26, 1913. Serial No. 781,417.

To all whom it may concern:

Be it known that I, CHARLES WALTER PARKS, a citizen of the United States, residing at Pomona, in the county of Los Angeles and State of California, have invented a new and useful Triples Cranking Mechanism; and I do hereby declare the following to be a full, clear, and exact description of the invention, such as will enable others skilled in the art to which it appertains to make and use the same.

This invention relates to a new and useful tripes cranking mechanism for operating a plurality of plungers or suckers one above the other in a single cylinder whereby a continuous liquid column may be lifted.

One of the features of the invention is the provision of means comprising a plurality of elements so connected to the plurality of plungers and to a single crank shaft, that three distinct motions may be imparted to the plungers. For instance, one plunger connects substantially direct with the crank shaft receiving a reciprocating motion, while the other two plungers individually receive reciprocating motions alternating with one another, and each in alternation with the first plunger. The second two plungers are connected to the crank shaft by bell crank levers and rod connections.

In practical fields the details of construction may necessitate alterations, to which the patentee is entitled, provided the alterations fall within the scope of what is claimed.

The invention comprises further features and combination of parts, as hereinafter set forth, shown in the drawings and claimed.

In the drawings:—Figure 1 is a view in elevation showing the improved cranking mechanism as applied to a pump having a plurality of plungers. Fig. 2 is a similar view partly in section showing parts of the cranking mechanism in different positions to those shown in Fig. 1. Fig. 3 is an edge elevation of Fig. 1. Fig. 4 is a plan view of Fig. 1. Fig. 5 is a sectional view on line 5—5 of Fig. 1. Fig. 6 is a detail perspective view of portions or parts of the cranking mechanism. Fig. 7 is a transverse sectional view on line 7—7 of Fig. 3.

Referring more particularly to the drawings, 1 designates a frame which may be of any suitable shape or construction, preferably triangular in side view, as shown in Fig. 1 having the supports 2, which are pro-

vided with guides 3, in which the cross heads 4, 5 and 6 are mounted. Mounted in bearings 7 of the frame, there being cap plates 8 secured by bolts 9, is a crank shaft 10. Connecting substantially the central portion of the crank pin 11 of the crank shaft is a pitman 12, which connects at 13 to the pins 14 of the cross head 4. The cross head 4 is provided with a plunger rod 15, which telescopes the cross head 5 and the tubular plunger rod 16, and to its lower end a plunger 17 is connected. The hollow plunger rod 16 telescopes the cross head 6 and the hollow plunger rod 18, and is provided with a plunger 19, which is interposed between the plunger 17 and the plunger 20, which plunger 20 is carried at the lower end of the plunger rod 18. The plungers 17, 19 and 20 operate in a single cylinder 21 as shown, and are designed to receive distinct reciprocating motions whereby a continuous liquid column may be lifted.

Journaled in bearings 22 at one side of the frame as shown in Fig. 1 are the pintles 23 of the bell crank lever 24, which comprises the arms 25 and 26. The arms 25 are connected at 27 and terminate in lugs 28, in bearings of which a pin 29 is arranged. Connecting the pin 29 and the crank pin 11 on one side of its center is a link 30. The arms 26 of the bell crank lever 24 are connected at 31 and terminate in lugs 32, between which the pitman 12 operates. The outer faces of the lugs 32 are provided with studs 33, to which the pitman rods 34 are connected, which in turn are pivoted upon the lugs 35 of the cross head 5. As shown in the drawings the bell crank lever 24 comprising the arms 25 and 26 (which are braced by the connecting rods 36) are constructed in the form of a casting.

Mounted in bearings 37 of the frame are the pintles 38 of the bell crank lever 39, the arms 40 of which are connected by the transverse bar 41 and terminate in extension arms 42 having lugs 43, to which the pitman rods 44 are pivoted. The pitman rods 44 are in turn pivoted to the lugs 45 of the cross head 6. The arms 47 of the bell crank lever 39 are connected as at 48 having lugs 49, in bearings of which a pin 50 is arranged. Connecting the pin 50 and the crank pin 11 is a link 51, whereby motion may be imparted to the bell crank lever 39. It will be observed that as the crank shaft operates, it raises and lowers the plunger

17, and at the same time oscillates the bell crank levers 24 and 39, which in turn impart alternating reciprocating motions to the plungers 19 and 20 and the cross heads 5 and 6. Each of the reciprocating motions of the plungers 19 and 20 alternate with the reciprocating motion of the plunger 17, and in this manner a continuous liquid column is being lifted.

10 The crank shaft is provided with a gear 53, with which a pinion 54 meshes, and to which pinion any suitable power may be coupled, whereby motion may be imparted to the gear and thence to the crank.

15 The invention having been set forth, what is claimed as new and useful is:—

A triplex cranking mechanism comprising a frame, a crank shaft mounted in bearings of the upper portion of the frame, a member adapted to be reciprocated mounted in guides of the lower portion of the frame having a pitman rod connection with the crank of the shaft and adapted to operate another element, a bell crank lever frame 25 pivotally mounted in each lateral end of

the first frame, a link connection connecting one end of each bell crank lever frame and the crank of said shaft, a second member adapted to be reciprocated mounted in said guides and having a rod connection with the other end of one of the bell crank lever frames, said second member designed to actuate a second element, a third member adapted to be reciprocated mounted in said guides and having a rod connection with one end of the other bell crank lever frame, said third member adapted to actuate a third element, a gear on one end of the crank shaft, and a crank and pinion for operating said gear and the crank shaft and the bell crank lever frames, which in turn actuate the several members.

In testimony whereof I have signed my name to this specification in the presence of two subscribing witnesses.

CHARLES WALTER PARKS.
